[57] CLAIM

The ornamental design for a combined store partition
and display cabinet, as shown and described.

DESCRIPTION

FIG. 1 is a top plan view of a combined store partition
and display cabinet showing my new design;

FIG. 2 is a front elevational view thereof;

FIG. 3 is a right side elevational view thereof, the left
side being a mirror image thereof;

FIG. 4 is a rear elevational view thereof; and,

FIG. 5 is a perspective view thereof on an enlarged
scale.

FIG. 4

FIG. 3

FIG. 1

FIG. 2

FIG. 5
